(57) **CLAIM**

(73) Assignee: **Kai R & D Center Co., Ltd.**, Seki (JP)

The ornamental design for a replaceable blade cartridge for cornea incising devices, as shown and described.

(***) Term: **14 Years**

(21) Appl. No.: **29/115,763**

DESCRIPTION

(22) Filed: **Dec. 20, 1999**

FIG. 1 is a front view showing a replaceable blade cartridge for cornea incising devices according to the present invention;

(30) **Foreign Application Priority Data**

FIG. 2 is a rear view showing the replaceable blade cartridge of FIG. 1;

Sep. 27, 1999 (JP) 11-26104

FIG. 3 is a plan view showing the replaceable blade cartridge of FIG. 1;

(51) **LOC (7) Cl.** **24-02**

FIG. 4 is a bottom view showing the replaceable blade cartridge of FIG. 1;

(52) **U.S. Cl.** **D24/146**

FIG. 5 is a right view showing the replaceable blade cartridge of FIG. 1, the left view being a mirror image thereof;

(58) **Field of Search** D24/146, 150,

FIG. 6 is a cross-sectional view taken along line 6—6 in FIG. 1;

D24/167; 606/107, 166; D28/45, 46, 47

FIG. 7 is a perspective view showing the replaceable blade cartridge of FIG. 1 from above; and,

(56) **References Cited**

FIG. 8 is a perspective view showing the replaceable blade cartridge of FIG. 1 from below.
